UNITED STATES PATENT OFFICE.

CHARLES A. HUSSEY, OF NEW YORK, N. Y., ASSIGNOR TO THE HUSSEY ELECTRIC COMPANY, OF SAME PLACE.

SIGNALING AND SWITCH APPARATUS FOR TELEPHONES.

SPECIFICATION forming part of Letters Patent No. 247,359, dated September 20, 1881.

Application filed April 9, 1881. (No model.)

To all whom it may concern:

Be it known that I, CHARLES A. HUSSEY, of New York, in the county and State of New York, have invented certain new and useful 5 Improvements in Signaling and Switch Apparatus Particularly Applicable to Telephones, of which the following is a specification.

These improvements are especially designed for use in a central office with which a number 10 of lines of telephone subscribers or customers communicate.

The improvements consist in the combination, with lines of telephone subscribers, of an electro-magnetic signal put in circuit with 15 said lines at a central office when communication is established between said lines, and adapted to be operated by a reverse electric current, to indicate when communication is no longer desired.

20 The improvements also consist in the combination, with lines of telephone subscribers, of signals whereby, when said lines are in communication, subscribers may call one another and signals at a central office which may be operated by a reverse electric current, to indicate when communication is no longer desired.

In the accompanying drawings, Figure 1 is a front view of one end of a signaling and switch apparatus embodying my invention. 25 Fig. 2 is a transverse vertical section of the apparatus, and Fig. 3 is a back view of the apparatus.

Similar letters of reference designate corresponding parts in all the figures.

30 I will now proceed to describe the apparatus in detail, premising that it comprises a system of signals for operation by the subscribers to indicate at the central office that they desire to be put in communication with some other subscriber, and a separate system of signals for operation by one of two subscribers put in communication, to indicate at the said office that the communication is no longer desired.

A designates a number of lines or wires, 45 (here shown as eight in number,) extending from subscribers' telephone-instruments. They are severally connected to flexible metallic strips B, which, as here shown, are fastened at one edge in vertical positions to the back of a board, C. At the lower end these flexible strips are severally connected to one finger,

D, of a pair of metallic spring-fingers, D D', and when the apparatus is in its normal position metallic plugs P, inserted in holes a in the front of the board C, fit between and electrically connect the spring-finger D D' of each pair. A wire, E, leads from each of the spring-fingers D' of the several pairs to metallic spring-fingers F, and in the normal condition of the apparatus it passes thence through metallic fingers G, then from the latter to the wire wound upon an electro-magnet, H, and thence to a ground-wire, I.

Near each of the electro-magnets H (as here shown in front of the same) is a drop, J, consisting of a plate hinged to a support at the lower end and held by a pin, a', slightly forward of a vertical position, so that it has a tendency to fall forward. A catch or hook, K, carried by the armature L of the electro-magnet H, and impelled downward by a spring, L', holds the drop in position when no electric current is passing through the circuit; but when an electric current generated by the magneto-electric machine M of a subscriber passes 75 through the circuit, the electro-magnet attracts its armature, and, raising the hook or catch, allows the drop to fall forward. Thus indication is given at the central office that the subscriber whose drop is thus operated desires to 80 be put into communication with another subscriber. The drop J, inasmuch as it makes a noise in falling forward against the front of the board C, is an audible as well as a visual signal. Each of these drops J has marked upon 85 it a number which indicates the subscriber to whom it belongs. Although these drops and their electro-magnets and armatures are shown as arranged in proximity to the board C, they may be arranged at some distance therefrom. 90

The subscribers' magneto-electric machines M are provided with commutators, so as to produce direct currents.

I do not confine myself to the use of any particular kind of magneto-electric machine, but 95 prefer to use the kind shown, and which I will now describe. Each of these machines has a circular permanent magnet, 1, with an armature, 2, which is rotated within the same by means of a cranked shaft, 3, connected to the 100 armature-shaft by gear-wheels 4 and 5. On the rear end of the armature-shaft is a commu-

tator, 6, against which bear metallic brushes 7, one of which is connected with the ground and the other of which may be connected with the subscribers' line A. The telephone-instruments at the subscribers' office and the means for switching them and the magneto-electric machines out of or into connection with their lines are not here shown, as they may be of ordinary form and constitute no part of my invention.

8 designates an electro-magnet and 9 designates a polarized armature therefor, supported by a spring, 10, extending from a hard-rubber block, 11, and capable of vibrating toward and from the electro-magnet.

12 designates a spring, against which the armature impinges when not otherwise actuated. The wire of the electro-magnet is connected with the spring 10, and hence currents of electricity will pass from it to the spring 10, thence through the armature to the spring 12, and off onto the line. A current of electricity passing through the wire of the electro-magnet attracts the armature, and thereby breaks the electric circuit. The electro-magnet, then becoming demagnetized, releases the armature and allows it to vibrate away and complete the circuit in a well-known manner. The armature thus causes a clapper, 13, mounted on it, to ring a bell, 14, constituting a call-signal.

In the board C, opposite the metallic spring-fingers F, are holes b, in which may be inserted a plug, O, to which is connected a wire, Q, leading to telephone receiving and transmitting instruments R S at the central office. When one of the drops J falls this plug O is inserted in the holes b, opposite the metallic spring-finger F, which was in circuit with the electro-magnet H, that controls said drop, and thereupon the plug separates that metallic spring-finger from the adjacent metallic finger G, cuts out or disconnects the said electro-magnet from the circuit, and the electric circuit then passes through the telephone instruments 45 to the ground. The person in charge of the central office can then ascertain with whom the subscriber desires to be put into communication. The drop J is then raised to its normal position.

50 On the front of the board C are bars N, arranged in pairs, and, as here shown, in a horizontal position. In these bars, and in the opposite portions of the board C, are holes c, in which the metallic plugs P may be inserted, so as to impinge against and make electrical connection between a pair of the bars and the outer edges of two of the flexible strips B, to put two subscribers in communication with each other. When the metallic plugs P are 55 removed from their holes a the connection between the spring-fingers D D' is broken and the electro-magnets H and drops J, which are connected electrically to the spring-fingers D', are cut out. The adjacent ends of each pair 60 of bars N are connected by wires T with the wire of an electro-magnet, U; hence one of the

electro-magnets U is put in circuit with two subscribers, who are put in communication with each other. Near, and as here shown in front of each of the electro-magnets, is a drop, V, 70 similar to the drops J, and controlled by a catch or hook, W, carried by a polarized armature, X, of said electro-magnet.

The subscriber who desires to be put in communication with another is always to be put 75 in connection by a plug, P, with that one of a pair of bars, N, which will cause the current of electricity generated by his magneto-electric machine to run along the wire of the electro-magnet U in the reverse direction to that in 80 which it will traverse the wire of the electro-magnets S. When the subscribers are put in communication the subscriber who caused the drop or signal J in the central office to fall forward operates his magneto-electric machine 85 again to call the subscriber with whom he is in communication. The wires T are connected to the wire of the electro-magnet U, so that electric currents will pass through the wire of said electro-magnet in a reverse direction to 90 that in which the electric currents will pass through the wire of the electro-magnets S adjacent to the subscribers' magneto-electric machines. Hence when the electro-magnets S attract their polarized armatures and operate 95 their signals the electro-magnet U will not attract its polarized armature or cause its drop or signal V to operate. Therefore the electric current generated by one subscriber operating his magneto-electric machine after being put 100 in communication with another subscriber effects the operation of the bell or signal 14 adjacent to the latter's magneto-electric machine and attracts his attention, but fails to operate the drop or signal V at the central office. It 105 also effects the operation of the bell or signal adjacent to the magneto-electric machine which is operated by the subscriber desiring to call the other subscriber with whom he has been put into communication, showing him that his 110 magneto-electric machine is in circuit. When the two subscribers have finished talking an electric current is sent over their circuit by one or other of their magneto-electric machines in a reverse direction to that previously sent over 115 their circuit by the subscriber desiring to communicate with the other. This may be done by turning the machine which was previously operated in the reverse direction or by turning the other machine in a direction suitable 120 for producing an electric current in a reverse direction to that previously generated. This reverse electric current will not cause the electro-magnets S adjacent to the magneto-electric machines to attract their armatures and 125 to actuate their signals, but will cause the electro-magnet U in the central office to attract its armature and actuate its signal, thus indicating that the subscribers have finished their conversation. By this means not only are the 130 subscribers allowed to converse in privacy and comfort without interruption from the central

office in the nature of inquiries through the telephone for the purpose of ascertaining whether they have finished, but they indicate at the central office when they have finished and obviate the necessity for so many employés there as are now required because this fact has to be ascertained through the telephone.

It will be observed that only one drop or signal, V, is provided for each pair of bars N. 10 This is all that will be necessary with the apparatus shown and described, and these drops or signals need not be numbered, as they and the pairs of bars are not exclusively appropriated to any particular subscriber or subscribers, but any pair of bars which happen to be unused are employed in establishing communication between two subscribers desiring to converse.

If desirable, the apparatus may be modified, 20 so that a single bar, N, instead of a pair of them, may be employed in connecting two subscribers. In this case there will be an electro-magnet, U, with the appurtenances thereof, and drop or signal V, in circuit between each 25 of the subscribers' lines A and flexible strips B. In other words, each of the lines A will communicate with an electro-magnet, U, and each of these electro-magnets will communicate with a flexible strip, B. Two subscribers 30 desiring to converse will then be put in communication by inserting two plugs, P, in the same bar N in positions to impinge against the

flexible strips B, which communicate with the lines A of such subscribers.

I do not confine myself to the use of the drops J and V, or either of them, as various other visual or audible signals may be employed in lieu thereof.

I do not claim any and all means whereby two subscribers put in communication at a central office may, when they no longer desire communication, indicate that fact at the central office through an annunciator or signal put into circuit with them.

What I claim as my invention, and desire to secure by Letters Patent, is—

1. The combination, with lines of telephone-subscribers, of an electro-magnetic signal put in circuit with said lines at a central office when communication is established between said lines, and adapted to be operated by a reverse electric current to indicate when communication is no longer desired.

2. The combination, with lines of telephone-subscribers, of signals whereby, when said lines are in communication, subscribers may call one another, and signals at a central office which may be operated by a reverse electric current to indicate when communication is no longer desired.

C. A. HUSSEY.
